UNITED STATES PATENT OFFICE.

WALLACE W. OZON, OF BROOKLINE, MASSACHUSETTS.

CENTRIFUGAL SWITCH.

Application filed July 15, 1924. Serial No. 726,121.

This invention relates to a centrifugal switch and has for its object to provide a mechanism which may be mounted at any suitable location upon a motor vehicle, being interposed in and forming a part of the electric circuit between a battery carried by said motor vehicle and the engine thereof, and being operatively connected to and driven by one of the front wheels of said vehicle, or any suitable portion of the transmission mechanism in such a manner that if the vehicle attains a predetermined speed, the electric circuit hereinbefore mentioned will be broken, thereby preventing the spark plugs of the engine from functioning and causing a reduction of the speed of the engine.

The invention consists of a centrifugal switch, as set forth in the following specification, and particularly as pointed out in the claims thereof.

Referring to the drawings:—

Figure 1 represents a side elevation of a switch embodying my invention, said switch being illustrated mounted upon a rod forming a part of the steering mechanism for the vehicle and being operatively connected to one of the front wheels of said vehicle.

Fig. 2 is a vertical section taken on the line 2—2 of Fig. 1.

Fig. 3 is a diagrammatic view illustrating the position of the switch in relation to the engine and storage battery of the motor vehicle.

Like numerals refer to like parts throughout the several views of the drawings.

In the drawings, 4 represents a main casing for a switch mechanism, said casing embodying therein a top member 5, a bottom member 6 and a side member 7, preferably cylindrical in form, said members all being securely held together by a plurality of tie rods 8. The main casing 4 has a chamber 9 provided therein in which a switch mechanism 10 is located, the latter being mounted upon a vertical shaft 11, in turn mounted to rotate in the top and bottom members 5 and 6 respectively of said casing. The lower end of the shaft 11 projects into a chamber 12 provided in an auxiliary casing 13, the latter being secured in any suitable manner to the under surface of the bottom member 6 of the main casing 4, and said shaft 11 has a bevel gear

14 fast to the lower end thereof, said bevel gear meshing with and being driven by a bevel gear 15 fast to a horizontal shaft 16 mounted to rotate in the auxiliary casing 13. The shaft 16 has a pinion 17 preferably constructed of insulating material, fast thereto which meshes with and is driven by a gear 18 which is fast to and rotates with a front wheel 19 of the motor vehicle.

The device, as a whole, is mounted upon an arm 20 constituting a portion of the steering mechanism of the vehicle, being clamped to said arm by a suitable clamping member 21 which is secured to the under surface of the auxiliary casing 13, and said auxiliary casing 13 and clamping member 21 are insulated from the arm 20 by a suitable insulating member 22 which is interposed therebetween.

Located within the chamber 9 upon the shaft 11, and preferably having screw-threaded engagement with said shaft is a cylindrical electric contact member 23, and also located upon said shaft 12 directly above the contact member 23 is a cylindrical insulating member 24 of the same diameter as said contact member, and said insulating member 24 is held tightly clamped against the upper extremity of said contact member by a suitable nut 25.

The switch mechanism 10 embodies therein a member 26 which is mounted to slide vertically upon the contact member 23, and also upon the insulating member 24, the normal position of said member 26, however, being upon the contact member 23 approximately as illustrated in Fig. 2. The switch mechanism 10 also embodies therein a pair of arms 27, the lower ends of which are pivotally secured at 28 to the member 26, and the upper ends of said arms being pivotally connected at 29 to a pair of weighted arms 30, the latter being, in turn, pivotally connected at 31 at their upper ends to a collar 32 constructed of insulating material, and fast to the vertical shaft 11.

A storage battery 33, or other suitable source of electric supply carried by a motor vehicle, is connected by a wire 34 with a binding post 35 which is mounted in the bottom member 6 of the main casing 4, said binding post being insulated from said bottom member. An arm 36 is loosely mounted upon the movable member 26 and is pre-

vented from rotating in unison with said member 26 by a rod 37 which projects downwardly therefrom and through an insulating member also mounted in the bottom member 6 of the casing 4.

The arm 36 is electrically connected to the binding post 35 by a suitable flexible electric conducting member 38. The arm 36 is still further electrically connected with the binding post 35 by a thin plate 39 which is fast to the binding post 35, said plate having an opening formed therein through which the rod 37 slides as the member 26 is raised and lowered by the switch mechanism. A binding post 40 is mounted in the top member 5 of the main casing 4, and said binding post is connected by a wire 41 to an engine 42 of the motor vehicle in the usual well known manner.

The general operation of the device hereinbefore described is as follows:—Assuming that the electric contact member 23 and the insulating member 24 have been located at a predetermined height within the main casing 4 in order that the device will operate to break the electric circuit therethrough when the motor vehicle attains a predetermined speed, the vehicle shaft 11 will be rotated continuously as long as the vehicle is in motion through its connection with the front wheel of said vehicle. The switch mechanism 10 operating in the usual well known manner will act to lift the member 26 vertically upon the contact member 23 as the vehicle speeds up, and if the speed of said vehicle becomes too great, the member 26 will be lifted entirely out of engagement with the contact member 23 and entirely into engagement with the insulating member 24, thereby breaking the electric circuit which enters the device at the binding post 25 and passes therefrom through the wire 38, arm 36, contact member 23, shaft 11, top member 5, binding post 40 and outwardly therefrom through the wire 41.

It is evident that when the electric circuit is broken that the spark plugs of the engine will refuse to function and the speed of the engine will, therefore, immediately be reduced, and said spark plugs will continue to fail to function until the speed of the motor vehicle has been reduced to such an extent that the member 26 again engages with the contact member 23.

It is evident that the switch mechanism of this device may be operatively connected and driven by any suitable portion of the transmission mechanism of a motor vehicle

without departing from the spirit of this invention.

60

I claim:—

1. A centrifugal switch comprising, in combination, a rotatable member, an electric contact member fast to said rotatable member and adjustable longitudinally thereof, an insulating member also mounted upon said rotary member in alignment with said electric contact member and also adjustable longitudinally upon said rotatable member, a movable contact member normally mounted upon said first-mentioned contact member, and centrifugally actuated means fast to said rotatable member and operatively connected to said movable contact member and adapted to move the latter longitudinally upon and out of engagement with said first-mentioned contact member and into engagement with said insulating member.

2. A centrifugal switch comprising, in combination, a rotary shaft, an electric contact member having screw-threaded engagement with said shaft, an insulating member also having screw-threaded engagement with said shaft and abutting against said contact member, means to rotate said shaft, a movable contact member slidably mounted upon said first-mentioned contact member, and centrifugally actuated means fast to said shaft and operatively connected to said movable contact member and adapted to move the latter in opposite directions into and out of engagement with said first-mentioned contact member to make or break an electric circuit passing therethrough.

3. A centrifugal switch comprising, in combination, a casing, a shaft rotatably mounted in said casing, a cylindrical electric contact member fast to said shaft, a cylindrical insulating member also fast to said shaft and aligning with said contact member, means to clamp said insulating member and contact member upon said shaft, a movable contact member normally located upon said first-mentioned contact member, and centrifugally actuated means fast to said shaft and operatively connected to said movable contact member and adapted to move the latter into and out of engagement with either said first-mentioned contact member or said insulating member to make or break an electric circuit passing through said shaft.

In testimony whereof I have hereunto set my hand.

WALLACE W. OZON.
